UNITED STATES PATENT OFFICE

CLARENCE E. NOERENBERG, OF LOS ANGELES, CALIFORNIA

BUILDING CONSTRUCTION

Application filed February 4, 1928. Serial No. 251,768.

This invention relates to building construction and while the features of the invention are applicable to the construction of buildings erected for any purpose whatever, the 5 invention is expected to be especially useful in the construction of both single and multiple family dwellings of one, two or three stories in height.

While modern engineering methods and 10 theoretical and applied scientific developments of recent years have been applied to the problems of construction of tall large buildings, such as skyscrapers, and of those in which the floors are expected to carry 15 heavy weights such as in warehouses, or buildings of special type such as factories, etc., the great majority of the smaller buildings of today are still being constructed with little advance beyond the methods of a century ago.

As these smaller buildings still are usually constructed, the raw materials are brought in their unfabricated form to the site where the building is to be erected and the structural 25 frame of the building is laboriously built up bit by bit by cutting each part to fit, by hand labor and attaching it to the parts already erected, usually without detailed drawings or directions and dependent on the individual 30 ability and skill of the workman. It is an unprogressive, wasteful, inefficient, slow and hand-labor method of construction, and the result is highly defective and must perforce in time exhibit its innate disadvantages. 35 Such a method takes very little advantage of the use of machinery and of modern production methods, and just as the structural frame is defective, so do the enclosing wall coverings fail that are hung upon it, whose function it is both to resist the elements and to 40 present the decorative qualities that the occupants desire.

Whether the exterior walls be of wood or brick or concrete, the wooden structural frame 45 of these buildings is subject to its own innate tendencies to shrink, warp, crack or swell and is subject to the hazards of weather, fire and rot and to the attacks of termites, vermin, etc., and in the fashion by which it is usually 50 non-rigidly and insecurely tacked or toe-

nailed together nowadays, it offers little resistance to the action of cyclones or earthquakes.

The general object of the present invention is to provide a building construction for a 55 structural frame of a building which contains none of these defects, which is homogeneous for both walls, floors and roof, the units of which can be fabricated in a factory by the use of machinery and under modern production methods with a minimum cost for hand labor and materials, and which can be erected on the site easily and quickly with a minimum use of hand labor and of heavy assembling machinery, and yet the units of which 60 are so adaptable that any style of plan, of 65 architecture, or of number of stories can be used with ease, quickness and economy.

A further object of the invention is to provide a building construction that has a structural frame the parts of which are made of a tough, rigid, light-weight homogeneous material, using this same material for floor, roof and wall elements, and which are readily assembled and so arranged and fastened 70 together that the floors and roofs are joined to the walls with "rigid joints" forming a "rigid frame" the walls of which are so rigidly braced that wind and earthquake, expansion and contraction, or movements between parts have little effect and little tendency to produce cracks in the wall covering. 75

A further object of the invention is to provide a building construction that produces an attractive, durable and relatively inexpensive 80 building in which the use of wood is avoided except as desired for decoration, thereby producing a building that is practically fire proof, termite proof, and vermin proof; and one in which the frame and its enclosing 85 covering will neither rot, shrink, warp, crack nor swell.

A further object of the invention is to provide a building construction that provides 90 wall units of such a type that furring and lathing materials on which the protective and decorative coverings of plaster and stucco are placed, and to which stone, brick, tile or terra cotta are anchored and tied, can be 95 supported directly on the frames of the

units either on one face or on both faces of the unit, (in the latter case leaving an air space between the faces) rendering the building warm in winter and cool in summer and giving the structure high insulating values against the transmission of heat and sound.

A further object of the invention is to provide a building construction that avoids the necessity of setting up a frame for the building as a separate operation, but that in the setting up of the wall units on the foundation to produce the walls of the structures upon which the lathing materials are directly hung, simultaneously at the places where the meeting edges or adjacent edges of the units come together, provides in that very meeting the structural columns (thereupon existent within the walls and integrally part of it) which are thereby immediately prepared to receive the loads that come from the second floor and/or roof beams or trusses to be supported at these junctions. The same operation and means that connect two wall units together to form the wall, simultaneously form the structural columns "built-in" within the wall.

A further object of the invention is to provide a construction for dwellings that contains wall units constructed and set up in such a way that they cooperate to form a structural frame for the building in which the beams or trusses are located in the meeting planes of the walls units and, rigidly attached to the structural columns formed at each junction of the wall units, so that they cooperate to form a rigid frame preventing the subsequent forming of cracks in the plaster on the interior of the walls.

A further object of the invention is to provide a building construction that contains a structural wall frame made up of wall units of rectangular ladder like form containing vertical side bars, one at each vertical edge of the unit, and horizontal crossbars spaced at intervals in the height of the unit the vertical side bars being so shaped and arranged that when two come together, one from each of adjacent units, and are fastened together, they form a structural column, that is to say, a "built-up" as well as "built-in" column that gives the wall strength and rigidity in itself and, to which the beams or trusses can be readily connected to the walls at the meeting planes of the units.

A further object of the invention is to provide a type of building construction which in addition to satisfying all of these aforesaid objects, is easily, efficiently and economically adaptable to all the infinite variations that exist in the design and erection of dwellings under the numberless different conditions that arise.

Further objects of the invention will appear hereinafter.

The invention consists in the novel parts

and combination of parts to be described hereinafter, all of which contribute to produce an efficient building construction.

A preferred embodiment of the invention is described in the following specification, 70 while the broad scope of the invention is pointed out in the appended claims.

In the drawings:

Figure 1 is a perspective showing a cross-section through a building in course of construction and embodying this invention, certain parts being broken away and shown in section so as to illustrate details of the invention.

Figure 2 is a view similar to Figure 1, but 80 illustrating a two-story building embodying the invention.

Figure 3 is a perspective illustrating the manner in which a beam such as a roof truss is supported on the structural column formed 85 by the junction of two wall units.

Figure 4 is a perspective showing the details of the lower end of a corner of the building illustrated in Figure 1.

Figure 5 is a perspective of the frame of a 90 typical wall unit and illustrating the way in which the crossbars for supporting lathing materials may be arranged.

Figure 6 is a view similar to Figure 5, but with certain parts broken away and showing 95 another wall unit in a position to match up with the wall unit shown in Figure 5; this view shows the way in which the lathing material is supported on the cross bars.

Figure 7 is a horizontal section particularly illustrating the preferred construction which is employed at the corners of the building; and

Figure 8 is a horizontal cross-section through the wall and illustrating the relation of the wall units.

Referring to Figure 1, A illustrates a house embodying the invention. It will be noted that the walls of this house are formed of wall units 1 supported on a foundation 3. 110 Two of these wall units are illustrated in Figures 5 and 6 in different stages of construction. The wall unit 2^a illustrated in Figure 5 embodies merely the steel frame of the unit. In other words, each of these wall units 115 is formed of a steel frame comprising two vertical side members 3^a, and a number of horizontal cross members 4 spaced at intervals. These side-members are preferably made of some structural shape such as channel iron 120 with a web 3^b and flanges 3^c. In any event, the vertical bar is built into the frame 2^a in such a way that it has a flange on the inner side of the wall for supporting the outer facing of the wall, and a flange on its inner side for 125 supporting the inner facing or plaster of the wall. For this purpose the flanges 3^c extend in the plane of the unit, that is, in the plane of the wall. In this way, when two of these frames are mounted or set up alongside of 130

each other in building the wall, the vertical bars cooperate to form a structural column. The integral web 3^b extends substantially through the entire thickness of the wall and determines the thickness of the wall. The side bars are preferably held slightly apart as will appear hereinafter.

In order to facilitate the attachment of plaster or stucco, the frame is provided with 10 girts or crossbars in the form of horizontal bars 4, the ends of which are welded to the vertical side-bars. The lathing materials are fastened directly to these cross-bars or, if desired, the wall unit may be made ready for 15 attaching various sorts of metal lath or stucco reinforcing by attaching vertical bars 5 to the bars 4, the points of contact 6 between these bars being tied with wire, or otherwise securely fastened. On the bars 5, which 20 would be on the inner side of the wall, lath, such as standard metal lath, 7 is attached. This same construction may be employed on the outer side, and back plastered also if desired. If desired, on the side of the frame 25 which is to form the outer side of the wall, wire mesh 9 carrying specially prepared paper 8 on its inner side can be attached. This wire mesh with the paper attached to it may be procured ready made. After the wall 30 units are set up alongside of each other in the manner described, and the wire mesh and/or metal lath attached thereto, stucco may be applied to the outer side of the wall and plaster to the inner side.

35 It should be understood that the wall unit described is a typical wall unit and the construction is such as it would have where the wall is without a window. Whenever the panel must carry a window, the panel is provided with cross-bars 10, such as illustrated in Figure 1, between which the window frame 11 is mounted.

40 At the lower end of each frame it is provided with two bars 12 which are attached on opposite sides of the vertical bars 3^a. These bars 12 are preferably in the form of angle iron with their vertical flanges welded to the flanges of the channels. Between these 45 bars 12, angle clips 13 are placed (see Figure 8) with their flanges welded to the edges of the flanges of the channels; the horizontal flanges of the clips are welded to the upper edges of the vertical flanges of the bars 12. The horizontal flanges of these clips have 50 holes to enable anchor bolts to be applied to secure the wall units to the foundation or foundation sills. Similar cross bars 12^a are provided to connect the side bars at the upper end of the frame.

55 The upper ends of the wall units are constructed so that they cooperate to facilitate the attachment of the roof trusses 14 of the building. For this purpose, the outer sides of the vertical side bars 3^a are provided with 60 gusset plates 15, which may be of the rec-

tangular form illustrated in Figures 5 and 6. When the panels are set up alongside of each other, these gusset plates 15 come into alignment but are slightly apart, so as to receive a vertical plate 16 which is provided at the end of a beam or truss (see Figure 3). This gusset plate 16 fits into position between the gussets 15, as illustrated in Figure 3, and is supported in position by bolts 17 placed in two vertically spaced holes which have been previously punched in the gussets. These bolts 17 have sufficient diameter to take up the shear due to the weight of the truss and roof and it is, therefore, unnecessary to provide any seat for the end of the truss to rest upon. The bolts should fit tight in the holes so that a rigid joint is formed between the truss and the column formed by the adjacent units.

70 The roof trusses may be of any desired construction. They would be constructed at the structural shop and preferably comprise a ridge plate 18 to which the truss members 19 are welded. In order to brace the trusses, each ridge plate is provided on opposite sides 75 with clips 20, to which horizontal ridge bars 21 are secured by means of bolts 22.

80 If it is desired to give the columns formed by the vertical bars 3^a, greater rigidity and a greater moment of inertia, this can be accomplished by providing one or more filler blocks or spacers in the form of thick plates, such as the plate 23. These plates may be welded on one side of each wall unit, but if desired aligning bolt holes may be provided in the vertical bars 3^a and loose spacer plates may be held in position, and bolted there when the wall is erected.

85 The invention may be embodied in a two-story building such as illustrated in Figure 2. This necessitates the use of floor beams 24 for the second story. The end of these beams are secured by bolts 25 between gusset plates 26 which project out from the vertical side bars 27 of the wall units 28. These gusset plates 26 are similar to the gusset plates 15 described in connection with Figures 5 and 6. At the heads of the columns 29 that are formed by the union of the vertical side bars of the wall units, similar gusset plates 30 are provided for supporting the roof trusses 31.

90 It will be noted that at the corners of the building the webs of the vertical side bars of the panels will not abut against each other so as to form a structural column of the same form as in the walls, the webs of the vertical bars are secured together by means of rigid angle clips 49 (see Figure 7) secured to the webs by the bolts 50. These clips cooperate 95 with the vertical members 51 of the panels to form a skeleton column. In forming the wall, this skeleton column may be built out to form a regular corner construction, as illustrated in Figure 7. In doing this, the rein-

forcing mesh 9 with the paper backing 8 is applied to the corner by bending the mesh to form an angle 52, coinciding with the true position of the corner of the building. If 5 desired, instead of extending the reinforcing and stucco out to form a right-angled corner, a beveled corner may be formed by applying the reinforcing wire and paper diagonally across the skeleton column, as indicated by 10 the dotted line 53.

What I claim is:

1. In a building construction, a wall composed of a plurality of wall units, said wall units having vertical side members and 15 mounted so that the side member of each units lies adjacent to the side member of the adjacent wall unit, each of said side members having an integral web extending substantially through the entire thickness of the 20 wall terminating at the ends of the unit, having a width determining the thickness of the wall, and having an outer flange extending substantially in the plane of the wall on the outer side of the wall, means secured to the 25 said flanges for attaching the outer facing of the wall to said unit, and means connecting each side member with the side member of its adjacent unit and cooperating with the 30 said flanges to form the structural column within the wall that supports the roof.

2. In a building construction, a wall composed of a plurality of wall units, said wall units having vertical side members and mounted so that the side member of each unit lies 35 adjacent to the side member of the adjacent wall unit, each of said members having an integral web substantially at right angles to the plane of the wall extending substantially through the entire thickness of the wall, terminating at the ends of the unit, having a 40 width determining the thickness of the wall, and having an inner flange extending substantially in the plane of the wall on the inner side of the wall, means attached to the said flanges 45 to carry the inner facing of the wall, spacers between the webs of the adjacent units, and means connecting each side member with the side member of its adjacent unit and cooperating with the 50 said flanges and webs to form the structural column within the wall that supports the roof.

3. In a building construction, a wall composed of a plurality of wall units, said wall units having vertical side members and 55 mounted so that the side member of each unit lies adjacent to the side member of the adjacent wall unit, each of said side members having an integral web extending substantially through the entire thickness of 60 the wall, terminating at the ends of the unit, having a width determining the thickness of the wall, and having a flange extending substantially in the plane of the wall on the outer side, with means for attaching the 65 outer facing of the wall to the outer flanges,

said side members also having flanges on their inner sides, with means attached to the same to carry the inner facing of the wall, and means connecting each side member with the side member of its adjacent unit and 70 cooperating with the said flanges to form the structural column within the wall that supports the roof.

4. In a building construction, a wall composed of a plurality of wall units, said wall 75 units having vertical side members and mounted so that the side member of each unit lies adjacent to the side member of the adjacent wall unit, each of said side members having an integral web extending substantially through the entire thickness of the wall terminating at the ends of the unit, 80 having a width determining the thickness of the wall and having a flange integral with the web extending substantially in the plane 85 of the wall toward the side face of the unit, means attached to the flanges for supporting the wall facing, means connecting each side member with the side member of its adjacent unit and cooperating with the said 90 flanges to form the structural column within the wall that supports the roof, and roof beams in a line with the meeting plane of the said side members and supported on the 95 said structural columns.

5. In a building construction, a wall composed collectively of a plurality of wall units forming the wall portion of the structural frame of a building, said wall units being formed of vertical side bars and of horizontal 100 cross bars spaced up and down at intervals all previously assembled and rigidly fastened together to form complete rigid structural frames or wall units of substantially rectangular shape, said wall units mounted on end 105 and edge to edge so that the side bar of one unit lies adjacent to the side bar of the adjacent unit with means connecting said two adjacent side bars to form a structural column and thereby simultaneously connecting 110 two adjacent units together and similarly successively connecting all wall units together to form a rigid continuous wall having integrally within it and part of it a series of "built-in" structural columns. The same 115 means that connects two or more wall units together to form the wall simultaneously forming said structural columns within the wall, and the said cross bars of successive units simultaneously forming the means of 120 support and fastening of lathing materials for carrying the whole wall covering.

6. In a building construction, a wall composed collectively of a plurality of wall units forming the wall portion of the structural 125 frame of the building, said wall units on opposite sides of the wall being of the same width as the distance between the roof beams of the building, and formed of vertical side bars and of horizontal cross bars spaced at 130

intervals all previously assembled and rigidly fastened together to form rigid structural frames or wall units of substantially rectangular shape, said wall units mounted on end and edge to edge so that one of said vertical side bars of each unit is adjacent to a side bar of the adjacent unit, means connecting said two adjacent side bars and cooperating with the same to form the structural columns "built-in" within the wall for supporting the roof beams, said horizontal cross bars being spaced at intervals and rigidly connecting the said side bars, and operating to brace and stiffen the said "built-in" columns, and thereby enable the parts of said columns to be of reduced dimensions, said vertical side bars and horizontal cross bars being integral portions of the wall unit and also forming the means of support and fastening of the lathing materials that enclose the whole structural frame.

7. In a building construction, a "rigid frame" forming the structural steel frame of a building made up of a wall on each side of a room or space and a set of floor beams and a set of roof beams or roof trusses, said walls being composed collectively of a plurality of wall units, said wall units on opposite sides of the wall being of the same width as the distance between the roof beams of the building, and being formed of vertical side bars and horizontal cross bars spaced at intervals previously assembled and rigidly fastened to the vertical side bars to compose such wall units, said wall units being mounted on end and edge to edge so that the side bar of one unit lies adjacent to the side bar of an adjacent unit, with means connecting these two adjacent side bars to form a structural column "built-in" integrally within the wall and thereby simultaneously connecting adjacent units to form a continuous wall having integrally within and part of it a series of "built-in" structural columns constituting the roof-supporting columns of the building, said set of floor beams being fastened each one separately and successively to, and supported by, the lower portion of such structural columns opposite each other within walls formed of said units on opposite sides of the room or space, said set of roof beams or roof trusses being fastened by a rigid connection each one separately and successively to, and supported by, the upper portion of such structural columns opposite each other within walls formed of said units on opposite sides of the room or space.

8. In a building construction, a pair of wall units whose planes are set at an angle to each other and forming a corner for the building, each unit consisting of a steel frame with side members having a flange lying substantially in the plane of the unit and a web extending substantially at right angles to the plane of the unit, said side members cooper-

ating to form the structural corner column for supporting a roof, means rigidly connecting the two adjacent side members, and wire mesh extending across the outer side of the corner with stucco carried thereby.

Signed at Los Angeles, California, this 1st day of February, 1928.
